UNITED STATES PATENT OFFICE

IVAR OSKAR ENGELBREKT SANDBERG, OF STOCKHOLM, SWEDEN

CIGAR MACHINE

Application filed January 30, 1931, Serial No. 512,440, and in Sweden February 6, 1930.

The invention has for its object to simplify the construction of the cigar-rolling machines at present in use.

With this and other objects in view the invention consists in certain constructions, improvements and combinations as will be hereinafter fully described and then specifically pointed out in the claims hereunto appended.

10 The invention is diagrammatically illustrated on the accompanying drawings on which Figs. 1, 2 and 3 are top plan view, side elevation and end elevation, respectively, of my machine.

15 Figs. 4 and 5 are side elevation and end elevation respectively, on an enlarged scale of a swinging arm carrying the rollers adapted to rotate the bunch, with the gears serving to rotate the rollers and a device for controlling the operation of a needle to clamp the wrapper against the bunch.

Fig. 6 is a plan view of a part of the swinging arm and parts of the needle controlling device.

20 Figs. 7 and 8 are end elevation and plan view, respectively, of two cutters with their supporting levers and parts of the rollers.

Fig. 9 is a view in end elevation of two supporting levers for the rollers and stops 25 to swing said levers.

Fig. 10 is a detail view necessary to the complete understanding of the mode of operation of the cutters.

The machine as illustrated comprises a 30 table 1 which may be supported at the proper height above the floor by any well known means not shown. A shaft 2 driven from any suitable source of power not shown is mounted below the table 1 and carries a cam cylinder 3 having a circumferential groove 4 and a cam groove 5 formed in one end surface of the cylinder 3. A roller 6 engages the groove 4 and is pivotally mounted at one end of a lever 7 carried by a vertical shaft 8 journalled in a bearing 9 at the top of the table 1 and carrying a lever 10 at its upper end.

A gear segment 11 is formed integral with the lever 10 and is in mesh with a gear 12 secured to the lower end of a sleeve 13 sur-

rounding a hollow shaft 14 extending through a bearing 15 at the top of the table 1. Mounted at the upper end of the sleeve 13 are an arm 16, a gear 17 and another arm 18 provided with a passage 19 communicating with the interior of the hollow shaft 14, through an aperture formed in the wall of the shaft 14. At its upper end the shaft 14 is closed by means of a threaded plug 20.

The opposite end of the lever 18 carries a depending sleeve 21 surrounding a tube 22 closed at its upper end by a threaded plug 25. The interior of the tube 22 communicates with the passage 19 through an aperture formed in the upper portion of the wall of the tube 22. At its lower end, the tube 22 carries a plate 23 supporting the wrapper carrier 24 in such a manner as to permit an easy removal thereof. The wrapper carrier 24 comprises a hollow member the interior of which communicates with the interior of the tube 22. The lower surface of the wrapper carrier 24 adapted to receive the wrapper is perforated whereby the wrapper may be held against the lower surface of the wrapper carrier by means of suction due to the partial vacuum existing in the tube 14 and transmitted through the passage 19 and the tube 22 to the interior of the wrapper carrier 24.

The arm 18 is apertured between its ends to receive a bolt 26 the upper and lower ends of which project from the arm 18 and support levers 27 and 28, respectively. A roller 30 is pivotally mounted on the lower lever 27 by means of a pin 29 while the upper lever 28 by means of a link 31 is connected to a lever 32 secured to the upper end of the tube 22. The pivots between the link 31 and the levers 28 and 32 are shown at 33.

A roller 34 engages the cam groove 5 and is pivotally mounted on a pin 50 mounted at one end of a bell-crank lever 35, 36 swingably mounted at one end of a shaft 42 journaled in a bearing 37 secured to the lower surface of the table 1.

38 represents a pin by means of which the upper end of the bell-crank lever 35, 36 is pivoted to a projection 39 from the lower surface of a support 40 for the cutting edge 41 (Fig. 1) corresponding to the desired contour 100

of the wrapper. Pivotedly mounted at the opposite end of the shaft 42 is a link 43 pivoted by means of a pin 44 to another projection 45 from the lower surface of the support 40. Between its ends the shaft 42 supports two horizontal levers 45 which at their opposite ends carry a pin 46. Pivotedly mounted on said pin 46 is a lever 47 extending upwards and parallelly with the arm 36 and 10 the link 43 and pivoted to a projection 49 from the front side of the support 40 by means of a pin 48.

The support 40 is perforated at its upper surface whereby a blank to be cut to form 15 a wrapper when laid down onto the support 40 is held thereagainst by means of suction produced by the partial vacuum existing in the interior of the support 40. The blank on the cutting edge 41 is cut to a wrapper 20 of the desired shape by means of two cutters described in detail later on and adapted to be moved over the cutting edge 41. The wrapper thus obtained is supplied to the wrapper support 24 when the support 40 under control of the groove 5 is moved upwards and inwards. Immediately before the support 40 reaches a position opposite the wrapper support 24 the bevelled end of a plunger 51 movable up and down in the support 40 strikes against a bevelled stop 52 mounted at the upper side of the table 1 whereby the plunger 51 raises the wrapper into engagement with the wrapper carrier 24 to which it adheres due to the suction 35 previously mentioned.

The arm 16 swings about the shaft 14 through an angle of about 180° under the control of the groove 4. Secured to the swinging arm 16 by means of bolts 54 is a plate 40 53 carrying a cam plate 55 attached to the plate 53 by means of bolts 56, and in addition the rolling mechanism comprising four rollers 58 rotated in the same direction and serving to rotate the bunch introduced therebetween. The rotary movement of the rollers 58 is derived from the arm 16 by means of a gear 60 pivotally mounted thereon and in mesh with a stationary gear 17. During the swinging movement of the arm 16 the gear 60 rolls on the gear 17 and rotates a bevel gear 61 in mesh with a second bevel gear 62 coupled to a gear 63 in mesh with a gear 64 engaging two gears 65 mounted on the upper rollers 58. The lower rollers 58 55 are in turn rotated by means of gears 77 inserted between the gears 65 and gears 66 mounted on the lower rollers 58. The rollers 58 are journaled in bell-crank levers 67 and 68 and the ends of the two upper rollers 58 60 project into arms 69 secured to bars 78 carried by the plate 53 to form stationary pivots for the levers 67 and 68 whereby the latter can be swung into the position as shown in Fig. 9 for the purpose of receiving a bunch 65 and delivering the finished cigar. The rollers

58 are opened and closed in the bunch receiving and cigar delivering positions, respectively, by means of stationary stops 70 and 71, respectively. Of these stops the stop 70 operates in the bunch receiving position by actuating a projection 72 from the lever 67 while the stop 71 operates in the cigar delivering position by acting upon a corresponding projection 73 from the lever 68. The levers 67 and 68 intermesh as shown at 75 75 and as a result it is sufficient to operate one only of the levers 67 and 68 in each of said two positions.

As may be seen from Figs. 7 and 8 two swingable levers 80 are mounted on the bars 78 beyond the rollers 58. Said levers 80 are interconnected by means of springs 81 and carry two rotary cutters 83 and 84 of conical shape. During the swinging movement of the arm 16 said cutters are moved over the blank placed on the cutting edge 41 to cut said blank to the desired shape the cutters 83 and 84 being pressed against the blank by means of the springs 81 and cutter 83 co-operating with the outer portion and cutter 84 with the inner portion of the cutting edge 41. The reason why the cutters 83 and 84 are conical in shape appears from Fig. 10 in which 86 denotes the generatrix of one of the cutters while 41 denotes the cutting edge on an enlarged scale. The blank is cut at where the generatrix 86 is in contact with the cutting edge 41.

The arm 16 carries a device to operate the needle 90 to clamp the end of the wrapper 100 against the bunch in the beginning of the wrapping operation. Said device comprises a swingable lever 92 supported by projections 91 depending from the lower surface of the arm 16. Secured to the lower end of said 105 lever 92 is a spring 93 which in turn carries a lever 94 the outer end of which forms a loop 95 which surrounds a pin 96 and situated between a member 97 conical at one end and an annular member 98 both secured to the 110 pin 96. The rear end of the pin 96 extends through an aperture 99 at one end of a support 100 secured to the plate 53. During the swinging movement of the arm 16 the upper end of the lever 92 strikes against a stop 101 115 attached to the lower surface of the gear 17 whereby the lever 92 is swung and the conical end of the member 97 pressed into engagement with a corresponding aperture 103 provided in the plate 53. The needle 90 is thereby pressed down to clamp the wrapper against the bunch. After the bunch has been rotated about one and a half revolutions the needle 90 will be returned to its initial position by means of the spring 93 when the 120 lever 92 leaves the stop 101.

The operation of the machine is as follows:

In the position of the swinging arm 16 and the rolling mechanism as illustrated in Fig. 1 in which position the lower rollers 58 occupy 130

the mutual position as shown in Fig. 9 a bunch is introduced in any well known manner from below between the rollers which are then closed upon the projection 72 (Fig. 9) leaving the stop 70 the rolling mechanism being swung counterclockwise (Fig. 1) by means of the members 8, 10, 12, 16 and 53 under control of the groove 4. At the same time the bunch is rotated about its axis as a result of the rolling of the gear 60 on the stationary gear 17. During this movement the arm 16 gradually reaches a position in which the cam plate 55 attached thereto strikes against the roller 30 which normally by means of a spring 110 is held in the position shown in full lines in which lever 28 is pressed against a stop 111 mounted on the arm 18 to hold the support 40 parallelly with the wrapper carrier 24. In the continued swinging movement of the arm 16 the lever 27 and as a result also the wrapper carrier 24 will be turned whereby the latter reaches the position represented by the broken line 120 at what time the arm 16 occupies the position represented by the broken line 121. Approximately in this position the wrapping of the wrapper at the lower surface of the wrapper carrier 24 onto the bunch situated between the rollers 58 and rotated thereby begins upon the needle 90 (Fig. 4) having entered a downwardly open recess 130 at the lower surface of the wrapper carrier 24 and been pressed down to clamp the inner end of the wrapper against the corresponding end of the bunch. The arm 16 continues its swinging movement and the rotating bunch removes the wrapper from the wrapper carrier 24 the latter being swung in such a manner about its pivot that the wrapper is wound smoothly onto the bunch. After the arm 16 has been swung through an angle of about 180° from the initial position the lower rollers 58 are opened in the manner illustrated in Fig. 9 in that the projection 73 strikes against the stop 71 whereby the finished cigar situated between the rollers 58 is delivered onto any suitable conveyor not shown.

During the swinging movement of the arm 16 between the bunch receiving and cigar delivering positions the cutters 83, 84 cut the blank placed on the cutting edge 41 in the lower position thereof to form a wrapper for the next cigar said wrapper being subsequently supplied to the wrapper 24 when the cutting edge 41 is raised under control of the groove 5. Should the operator not find time to stretch the blank before the cutters 83, 84 reach the cutting edge this may be done afterwards upon the cutters having passed the cutting edge 41 because said cutters are operative to cut a blank also when the arm 16 after having discharged the cigar is returned to its initial position clockwise to receive another bunch. Accordingly the cutting edge 41 preferably is not raised towards

the wrapper carrier 24 until after the cutters 83, 84 during the return movement of the arm 16 have passed the cutting edge 41.

By replacing the cam plate 55 by similar cam plates of different shape bunches differing in shape may be wrapped in the machine. If desired the rotary speed of the bunch when the wrapper is wound thereon may be varied to secure a smooth wrapping of the wrapper onto the bunch by turning the gear 17 about its axis by suitable means not shown, preferably under control of a replaceable cam cylinder. Obviously the arm 16 upon having delivered the wrapped bunch may continue to rotate in the same direction and thus revolve in one direction only, stopping for a moment in two positions during each revolution about 180° apart to receive a fresh bunch and deliver a wrapped bunch. If desired the machine when operating in this manner may be arranged to wrap a bunch also during the latter part of the revolution, that is when moving from the cigar delivering position into the bunch receiving position.

The machine may be adapted for use in wrapping both halves of a tobacco-leaf simply by providing the means for rotating the bunch about its axis with a reversing gearing not shown, preferably by substituting such a gearing for the bevel gears 61, 62 whereby the bunch during the movement from the bunch receiving position into the cigar delivering position may be rotated in either direction about its axis to enable the wrapping of both halves of a tobacco-leaf in one and the same machine.

What I claim is:—

1. In a cigar wrapping machine, a swinging arm, wrapping rollers carried by said arm and adapted to be moved thereby between a bunch receiving position and a cigar delivering position, a wrapper carrier mounted in the path of said wrapping rollers and arranged to cooperate therewith to wrap a bunch during the movement between said two positions, wrapper cutters carried by said arm and movable therewith, and a cutting edge normally situated in the path of said cutters to cooperate therewith to cut a wrapper during the movement between said two positions and movable back and forth between the path of said cutters and said wrapper carrier to transfer the wrapper cut to said wrapper carrier.

2. In a cigar wrapping machine, a swinging arm, wrapping rollers carried by said arm and adapted to be moved thereby between a bunch receiving position and a cigar delivering position, a wrapper carrier mounted in the path of said wrapping rollers and arranged to cooperate therewith to wrap a bunch during the movement between said two positions, wrapper cutters carried by said arm and movable therewith, and a cutting edge normally situated in the path of said

- cutters to cooperate therewith to cut a wrapper during the movement between said two positions and movable back and forth between the path of said cutters and said wrapper carrier to transfer the wrapper cut to said wrapper carrier, and stops adapted to open said wrapping rollers in the bunch receiving and cigar delivering positions.
3. In a cigar wrapping machine, a swinging arm, wrapping rollers carried by said arm and adapted to be moved thereby between a bunch receiving position and a cigar delivering position, a wrapper carrier mounted in the path of said wrapping rollers and arranged to cooperate therewith to wrap a bunch during the movement between said two positions, wrapper cutters carried by said arm and movable therewith, and a cutting edge normally situated in the path of said cutters to cooperate therewith to cut a wrapper during the movement between said two positions and movable back and forth between the path of said cutters and said wrapper carrier to transfer the wrapper cut to said wrapper carrier, means for rotating said wrapping rollers about their axes during the movement between said two positions and comprising a reversing gearing permitting rotation of said rollers in either direction for the purpose set forth.
4. In a cigar wrapping machine, a swinging arm, wrapping rollers carried by said arm and adapted to be moved thereby between a bunch receiving position and a cigar delivering position, a wrapper carrier mounted in the path of said wrapping rollers and arranged to cooperate therewith to wrap a bunch during the movement between said two positions, wrapper cutters carried by said arm and movable therewith, and a cutting edge normally situated in the path of said cutters to cooperate therewith to cut a wrapper during the movement between said two positions and movable back and forth between the path of said cutters and said wrapper carrier to transfer the wrapper cut to said wrapper carrier, means for swinging said arm, a gear concentrically mounted with respect to the swinging axis of said arm and in mesh with a second gear pivotally mounted on said arm and coupled to said wrapping rollers to rotate said rollers during the movement thereof between said two positions.
5. In a cigar wrapping machine, a swinging arm, wrapping rollers carried by said arm and adapted to be moved thereby between a bunch receiving position and a cigar delivering position, a wrapper carrier mounted in the path of said wrapping rollers and arranged to cooperate therewith to wrap a bunch during the movement between said two positions, wrapper cutters carried by said arm and movable therewith, and a cutting edge normally situated in the path of said cutters to cooperate therewith to cut a wrapper during the movement between said two positions and movable back and forth between the path of said cutters and said wrapper carrier to transfer the wrapper cut to said wrapper carrier, a needle carried by said arm and adapted to be operated as a result of the swinging movement thereof to clamp one end of the wrapper against the bunch for the purpose set forth.
6. In a cigar wrapping machine, a swinging arm, wrapping rollers carried by said arm and adapted to be moved thereby between a bunch receiving position and a cigar delivering position, a wrapper carrier mounted in the path of said wrapping rollers and arranged to cooperate therewith to wrap a bunch during the movement between said two positions, wrapper cutters carried by said arm and movable therewith, and a cutting edge normally situated in the path of said cutters to cooperate therewith to cut a wrapper during the movement between said two positions and movable back and forth between the path of said cutters and said wrapper carrier to transfer the wrapper cut to said wrapper carrier, a needle carried by said arm and adapted to be operated as a result of the swinging movement thereof to clamp one end of the wrapper against the bunch for the purpose set forth.
7. In a cigar wrapping machine, a swinging arm, wrapping rollers carried by said arm and adapted to be moved thereby between a bunch receiving position and a cigar delivering position, a wrapper carrier mounted in the path of said wrapping rollers and arranged to cooperate therewith to wrap a bunch during the movement between said two positions, wrapper cutters carried by said arm and movable therewith, and a cutting edge normally situated in the path of said cutters to cooperate therewith to cut a wrapper during the movement between said two positions and movable back and forth between the path of said cutters and said wrapper carrier to transfer the wrapper cut to said wrapper carrier, a cam plate carried by said arm and adapted to swing said wrapper carrier during the wrapping of the bunch.
- In testimony whereof I affix my signature.
- IVAR OSKAR ENGELBREKT SANDBERG.
